UNITED STATES PATENT OFFICE.

DANIEL W. SMITH, OF CHICAGO, ILLINOIS, ASSIGNOR TO INTERNATIONAL HARVESTER COMPANY, OF CHICAGO, ILLINOIS, A CORPORATION OF NEW JERSEY.

HOIST FOR CORN-SHOCKERS.

SPECIFICATION forming part of Letters Patent No. 782,072, dated February 7, 1905.

Application filed March 5, 1904. Serial No. 196,762.

To all whom it may concern:

Be it known that I, DANIEL W. SMITH, a citizen of the United States, and a resident of Chicago, in the county of Cook and State of Illinois, have invented certain new and useful Improvements in Hoists for Corn-Shockers, of which the following is a specification sufficiently clear and exact to enable those skilled in the art to which it appertains to make and use the same.

The invention relates in general to hoists, and in particular to hoists for corn-harvesters of the type in which a shock of corn is formed upon a platform and is lifted therefrom and swung upon one side and deposited upon the ground by means of a crane.

The object of the invention is to provide a hoist the operating-lever of which serves to turn the crane, whereby the operation of lifting the shock from the harvester and depositing it upon the ground is facilitated. Heretofore the cranes for such harvesters have usually been provided with a winch having a crank by which it is operated and a lever independent thereof for turning the crane. Such a construction necessitates, first, the raising of a shock a sufficient amount to clear the platform and the guard around the outside thereof by turning the crank of the winch and locking the same to hold the shock in its elevated position; second, the turning of the crane by means of the lever to swing the shock to one side preparatory to depositing it upon the ground, and, third, the releasing of the winch to lower the shock. Since the machine is at rest during the operation of depositing the shock, its efficiency depends considerably upon the time required to perform this operation. It is therefore essential that this time be reduced to the minimum. The present invention, an embodiment of which is shown in the accompanying drawings, very materially lessens this time by performing the three operations above referred to by means of a single lever, thus increasing the efficiency of the machine.

Referring to the drawings forming a part of this specification, in which like characters of

reference designate like parts, Figure 1 illustrates as much of a corn-harvester of the above-described type as is necessary to show the application of the invention. Fig. 2 is an elevation of the inner side of the hoist and its operating-lever, showing the latter in its highest position and showing also a fragment of the mast of the crane to which the hoist is attached. Fig. 3 is an elevation corresponding to Fig. 2, showing the operating-lever in its lowest position. Fig. 4 is a plan view of the parts shown in Figs. 2 and 3, showing the operating-lever in its medial position, in which the radial links are substantially horizontal. Fig. 5 shows a modification in the construction of the pawl and ratchet.

Referring to Fig. 1, A designates the traction-wheel; B, the framework of the gathering devices; C, the shield around the outer edge of the platform; D, the mast of the crane; D', the members of the tripod supporting the same, and D'' the shock-forming post having folding radial arms d, by which the shock is lifted. All these parts are common to corn-harvesters of this type and need not be further described here.

Mounted upon the mast D of the crane is a hoist having a winding-drum E and an operating-lever F. The winding-drum is connected with the shock-forming post by means of the usual rope d', and the operating-lever is connected with the winding-drum by means hereinafter described, by which it is turned. The winding-drum E is journaled on a shaft e, carried by the bracket E', secured to the mast. This drum is provided with ratchets e', which are adapted to be engaged by pawls e'', which are pivotally connected with radial links e'', by which they are held in proper position relative to the ratchets, one end of each of which links is pivoted on the shaft e. Reacting between the pawls and the radial links are the springs e'', which serve to hold the pawls into engagement with the ratchets when the former are unrestrained. The lever F is preferably provided with a yoke f at the end adjacent to the mast, between the members of which the mast is received and by which it is pivotally

connected therewith in the usual manner, so that it serves to turn the crane and yet is free to vibrate in a transverse plane. The links f' are provided to connect the radial links e' 5 with the lever F and are preferably pivoted on opposite sides of the inner member of the yoke f. Their connection with the radial links is preferably made by means of the pivots for the pawls. Yokes f'' are provided at 10 the upper end of these links to support the outer ends of the pivot-pins.

From the above description it will be seen that if the lever F be reciprocated in the plane of the mast the pawls will alternately engage 15 the ratchets, moving the latter intermittently in one direction, one pawl engaging on the upward movement of the lever and the other pawl on the downward movement thereof. By these means the shock may readily be 20 lifted and be swung to one side of the machine preparatory to depositing it upon the ground. A support f'' is provided to carry the operating-lever, which by its engagement therewith serves to hold the crane in its normal position 25 during the formation of the shock.

In order to release the winding-drum to lower the shock, it is necessary to provide means for disengaging the pawls from the ratchets. The means herein shown consist 30 of latch-handles G, which are pivoted in the usual manner to the outer end of the lever F and connected to the pawls through the agency of connecting-rods g' , bell-cranks g'' , and links g''' , which latter are provided with a flexible 35 portion g^4 , herein shown in the form of a chain. By these means it will be seen that the winding-drum may be released and the shock dropped to the ground, or it may be lowered to the ground gradually by alter- 40 nately releasing the pawls. In order to readily disengage the pawls from the ratchets, it may be found desirable to provide the former with antifriction-rollers, as shown in Fig. 5, and to shape the ratchets in conformity therewith, 45 in which instance it will be necessary to reduce the number of ratchets.

The operation of the invention is substantially as follows: A shock is accumulated upon the platform of the harvester in any desired manner and bound. It is then lifted from the 50 platform clear of the shield around the outer edge thereof by the operator, who simply reciprocates the operating-lever in the plane of the mast, thereby turning the winding-drum. The shock is then swung from the platform 55 to one side of the machine by means of the same operating-lever, after which the winding-drum is released by means of the latch-handles to drop the shock, or it may be lowered gradually to the ground by operating the 60 latch-handles alternately and reciprocating the operating-lever in a reverse direction to that employed in raising the shock. The shock-forming post is then disengaged from the shock in the usual manner and returned 65 to the platform by repetition of the operation above described.

Having thus described my invention, what I claim as new, and desire to secure by Letters Patent, is—

In a corn-shocker, the combination with the crane, of a shock-forming post, a winding-drum provided with ratchets mounted upon the crane and connected with said post, a lever pivotally connected with the crane independent of the support for said drum which shall operate to revolve the crane, means, comprising a plurality of toggles connecting said drum and lever each having a pawl which is adapted 75 to engage the ratchets, whereby said drum may be rotated by each stroke of said lever and latch-handles connected with the pawls for throwing each out of engagement with the ratchets to permit retrograde rotation of said drum.

In testimony whereof I have signed my name to this specification in the presence of two subscribing witnesses.

DANIEL W. SMITH.
